CLAIM

The ornamental design for a wheel for a toy vehicle, as shown and described.

DESCRIPTION

FIG. 1 is a top perspective view of a wheel for a toy vehicle showing our new design;

FIG. 2 is a front elevational view thereof, the rear elevational view, the top plan view and the bottom plan view being identical; and,

FIG. 3 is a side elevational view thereof, the other side being identical.

FIG. 3

FIG. 2

FIG. 1
